(57) **CLAIM**

The ornamental design for a guitar pick for strumming, as shown and described.

DESCRIPTION

FIG. 1 is a top front perspective view of a first embodiment of a guitar pick for strumming, showing my design;

FIG. 2 is a front elevation view of the first embodiment of the guitar pick for strumming;

FIG. 3 is a rear elevation view of the first embodiment of the guitar pick for strumming;

FIG. 4 is a left elevation view of the first embodiment of the guitar pick for strumming;

FIG. 5 is a right elevation view of the first embodiment of the guitar pick for strumming;

FIG. 6 is a top plan view of the first embodiment of the guitar pick for strumming;

FIG. 7 is a bottom plan view of the first embodiment of the guitar pick for strumming.

FIG. 8 is a top front perspective view of a second embodiment of the guitar pick for strumming, showing my design;

FIG. 9 is a front elevation view of the second embodiment of the guitar pick for strumming;

FIG. 10 is a rear elevation view of the second embodiment of the guitar pick for strumming;

FIG. 11 is a left elevation view of the second embodiment of the guitar pick for strumming with a right elevation view being a mirror image of the left elevation view;

FIG. 12 is a top plan view of the second embodiment of the guitar pick for strumming; and,

FIG. 13 is a bottom plan view of the second embodiment of the guitar pick for strumming.

The broken lines shown in the drawings depict portions of the guitar pick for strumming that form no part of the claimed design.

1 Claim, 11 Drawing Sheets
